U.S. Appl. No. 29/300,742, filed May 1, 2008 in the name of Julien Metzger entitled Pneumatic Tire.

* cited by examiner

Primary Examiner — Stacia Cadmus

(74) Attorney, Agent, or Firm — Buchanan Ingersoll & Rooney PC

(57) **CLAIM**

The ornamental design for a tire tread for pneumatic tire, as shown and described.

DESCRIPTION

FIG. 1 is a perspective view of a tire tread for pneumatic tire showing our new design, it being understood that the tread pattern repeats circumferentially about the outer circumference and shoulder of the tire.

FIG. 2 is a left side elevational view, the right side elevational view being a mirror image thereof; and,

FIG. 3 is a front elevational view, the rear elevational view being a mirror image thereof.

The broken line disclosure of the tire sidewall and inner bead depicts environmental subject matter that forms no part of the claimed design.
